UNITED STATES PATENT OFFICE.

SAMUEL S. CORNELIUS, OF COMMERCE, TEXAS.

FURNACE.

1,261,103.

Specification of Letters Patent. Patented Apr. 2, 1918.

Application filed June 9, 1917. Serial No. 173,767.

To all whom it may concern:

Be it known that I, SAMUEL S. CORNELIUS, a citizen of the United States, residing at Commerce, in the county of Hunt and State 5 of Texas, have invented a new and useful Furnace, of which the following is a specification.

The present invention appertains to furnaces, and aims to provide a novel and improved furnace adapted especially for use 10 outdoors for heating a wash pot or kettle.

It is the object of the invention to provide a furnace of the nature indicated which is simple and inexpensive in construction, 15 and which embodies a novel assemblage of the component elements, the device having novel means for accommodating the kettle.

With the foregoing and other objects in view which will appear as the description 20 proceeds, the invention resides in the combination and arrangement of parts and in the details of construction hereinafter described and claimed, it being understood that changes in the precise embodiment of the 25 invention herein disclosed can be made within the scope of what is claimed, without departing from the spirit of the invention.

The invention is illustrated in the accompanying drawings, wherein:

30 Figure 1 is a front view of the furnace, portions being broken away;

Fig. 2 is a plan view with the kettle cover and bail removed, and portions broken away and shown in section;

35 Fig. 3 is a detail view of the upper end of one of the upright supporting bars.

The casing 1 of the furnace is formed from a plate of sheet metal set on edge and bent so that its ends overlap, as at 2, at the 40 rear of the furnace. A vertical supporting and stiffening bar 3 is riveted or otherwise secured to the inner overlapped end of the plate, and the overlapped portions are clamped together by a suitable number of

45 bolts 4 which also preferably extend through the bar 3, the outer overlapped portion having slots 5 for the bolts 4 in order that the casing can be adjusted to accommodate various kettles or pots. Up-

50 right supporting bars 6 are suitably secured to the side walls of the jacket at the interior thereof. The bars 3 and 6 serve to strengthen the casing and relieve the same of undue strains, the lower ends of the bars 55 being bent back inwardly, as at 7, to provide feet, and to also provide shoulders or

ledges for supporting the grate 8 between the bars above the ground on which the casing is set. The grate 8 is used when coal is burnt, but can be eliminated when wood 60 is used as fuel. The front wall of the casing 1 has a fuel door 9, and is also provided with a draft damper 10 for controlling the flow of air into the casing below the grate. Suitable handles 11 are attached 65 to the side walls of the casing 1 near its upper end in order that the casing can be readily carried.

The upper ends of the bars 6 are notched, as at 13, to support the outstanding ears or 70 eyes 14 at the opposite sides of the rim of the kettle 15, whereby the bars 6 sustain the greater portion of the weight of the kettle and its contents.

The ears 14 in seating in the notches 13 75 hold the kettle in proper position, and the upper edge of the casing 1 projects above the bars 6 to surround the rim of the kettle. The ears 14 have the usual bail 16 connected thereto in order that the kettle can be 80 readily handled. The bars 6 being disposed at opposite sides of the kettle and grate bulge the side walls of the casing 1 outwardly, as at 17, to provide crescent shaped outlet flues 18 for the products of combustion which circulate around the walls of the kettle for heating it. The kettle 13 has a cover 19 provided with a handle 20. The rim of the kettle seats upon the front wall of the casing 1 and upon the upper end of 90 the rear bar 3.

When the furnace is used with small kettles or pots, the supporting bars 3 and 6 can be eliminated, and the rim of the kettle or pot can rest directly on the upper edge 95 of the casing which is contracted to embrace the kettle or pot, the outstanding ears 14 of the kettle serving to bulge the upper edge of the casing outwardly for the outlet of the products of combustion.

Having thus described the invention, what is claimed as new is:

1. A furnace embodying a casing adapted to receive a kettle, the casing being adjustable to receive kettles of different sizes and 105 having means for preventing undesired expansion thereof, and upright bars secured interiorly to the walls of the casing for supporting the kettle and bulging the casing outwardly to provide outlet flues.

2. A furnace embodying a casing adapted to receive a kettle, upright bars secured in-

teriorly to the walls of the casing for supporting the kettle and bulging the casing outwardly to provide outlet flues, said bars having ledges near their lower ends, and a 5 grate seatable upon said ledges between the bars to assist in bulging the casing.

3. A furnace embodying a casing for receiving a kettle, and a pair of opposite upright bars secured interiorly to the walls of 10 the casing and having their upper ends notched to support the ears of the kettle, said bars bulging the corresponding walls of the casing outwardly to provide outlet flues for the products of combustion and to 15 receive said ears.

4. A furnace embodying a casing com-

prising a plate set on edge and bent so that its ends overlap, adjustable means for clamping the overlapped portions together, opposite bars secured interiorly to the walls 20 of the casing and arranged in an upright position for supporting a kettle therebetween and bulging the casing outwardly to provide outlet flues.

In testimony that I claim the foregoing 25 as my own, I have hereto affixed my signature in the presence of two witnesses.

SAMUEL S. CORNELIUS.
